PAPER TOWELING

Mary Ellen Wassenberg, Green Bay, Wis., assignor to Fort Howard Paper Company, Green Bay, Wis.

Filed Mar. 25, 1971, Ser. No. 128,210

Term of patent 14 years

Int. Cl. D6—13

U.S. Cl. D59—2 A

The figure is a top plan view of paper toweling showing my new design, the design being comprised of the lace configuration together with the contrast, the surface being continuous and dimpled throughout as indicated in the lower left corner, the remainder of the dimpling having been omitted for purposes of simplifying the drawing, a full width of the design being shown from top to bottom of the figure, the design being of indeterminate length.

I claim:

The ornamental design for paper toweling, as shown and described.
